UNITED STATES PATENT OFFICE

LAURENCE M. PERSONS, OF ST. LOUIS, MISSOURI

DRAFT CONTROL MEANS

Application filed May 8, 1930. Serial No. 449,371.

My invention relates to combustion control means, for example, for furnaces, and has for one object to provide thermostatically responsive control means for a furnace. One object of my invention is to provide control means for the air inlet and for the check draft of a furnace. Another object is a provision of control means which shall be simple to install and efficient in operation. Other objects will appear from time to time in the course of the specification and claim.

I illustrated my invention more or less diagrammatically in the accompanying drawings, wherein Figure 1 is a section of a building with parts in elevation. Figure 2 is a section on the line 2-2 of Figure 1, and Figure 3 is a section on the line 3-3 of Figure 2.

Like parts are indicated by like symbols throughout the specification and drawings.

Referring to the drawings, A generally indicates any suitable furnace which may have, for example, the fuel inlet door A¹ and the usual air inlet A². A³ indicates the flue or outlet for the exhaust products of combustion. A⁴ indicates air outlets for the air heated by the furnace. It will be understood that I do not limit myself to the employment of my invention with a furnace associated with a hot air heating system, and its application thereto, as shown in the accompanying drawings, is merely illustrative.

B indicates diagrammatically a thermostat adapted to respond to house temperatures. This thermostat is included in a circuit which includes the conductive line B¹ extending from one end of the secondary coil B² of the transformer. B³ extends from the opposite end of said coil. B⁴ indicates the primary coil of the said transformer, and B⁵ the energizing circuit for said primary coil which may, for example, be energized by a commercial electric power. In order to conform to underwriters' requirements, the current may be stepped down to, say, 25 volts.

Included in the circuit B¹ B³ are a plurality of resistance coils C. Each such coil may be wound about any insulating and refractory member C¹, as illustrated, although I do not wish to limit myself specifically to any par-

ticular type of resistance. The important fact is that I provide electrically operated heating or motor means in a circuit controlled by the temperature control room thermostat.

Each such resistance has adjacent it a bimetallic strip C² indicated as coiled, as shown in Figure 3. One end of each such strip is secured as at C³ and the rest of the strip is free to flex, with the limitation that the opposite end is secured, as at C⁴, to any suitable rotatable member or pin C⁵. The pin C⁵ has a fixed position or axis of rotation and may be provided, for example, with the bearing C⁶ associated with a housing C⁷ to house the simple heat motor above described. It will be understood that when the actuating circuit is closed as by the operation of the thermostat, the coil C is heated by the passage of current therethrough, and causes the bi-metallic strip C² to flex. The flexure of said strip rotates the pin C⁵ and with it the butterfly valve C⁸ mounted thereupon. One of said valves may be positioned within the air inlet A² and the other within the check inlet A¹⁰ in communication with the exhaust outlet or flue A³. The parts are so disposed that when the thermostat calls for heat the valve in the check inlet A¹⁰ is closed and the valve in the air inlet A² is opened. Corresponding, when the thermostat calls for a cessation or reduction of heat the change in the temperature to which the heat motors are subjected reverses the previous action, and closes the valve controlling the air inlet A² while opening the valve controlling the check passage A¹⁰.

It will be realized that whereas I have described and shown a practical and operative exemplification of my invention, nevertheless I do not wish to be limited precisely or specifically thereto. In a broad sense I wish my drawings and description to be taken as illustrative, rather than as limiting me to the precise details shown, except so far as I limit myself by my claim.

I claim:—

In a control means for a valve, a valve member including a valve stem, a casing having an aperture therein in which one end of the valve stem is journaled, a coil thermostat in the casing having one end secured to

the side thereof and having its other end attached to said valve stem, a core in said casing extending across and supported by the side walls of the casing and spaced below the thermostat, a resistance element on said core in circuit with thermal control means for flexing said thermostat, and means for supporting said casing.

5 Signed at St. Louis, Missouri, this 29th
10 day of April, 1930.

LAURENCE M. PERSONS.
